UNITED STATES PATENT OFFICE.

HENRY ROREBECK, OF PARMA, ASSIGNOR TO ANDREW V. SMITH, OF ROCHESTER, NEW YORK.

COMBINED BRIDLE AND HALTER.

SPECIFICATION forming part of Letters Patent No. 295,812, dated March 25, 1884.

Application filed October 12, 1883. (No model.)

To all whom it may concern:

Be it known that I, HENRY ROREBECK, a citizen of the United States, residing at Parma, in the county of Monroe and State of New York, have invented certain new and useful Improvements in Rope Halters and Bridles; and I do hereby declare the following to be a full, clear, and exact description of the invention, such as will enable others skilled in the art to 50 which it appertains to make and use the same, reference being had to the accompanying drawing, and to letters or figures of reference marked thereon, which form a part of this specification.

55 My invention is a combined halter and bridle, and embraces the following peculiar features: the headstall, cheek-straps, bit-rings, and hitch-rope, all formed of one and the same piece of halter-rope; also, the forestall or front- 60 let and nose-strap, fastened to said rope in proper position by rivets; and, lastly, a cruciform throat-latch having upon the lower ends and the off-side upper end suitable rings by which to attach the same to the branches of the hitch-rope, and upon the near-side upper end a suitable snap-hook by which to secure the device upon the horse's head, all of which is hereinafter more fully described, and illustrated by the accompanying drawing, in which 65 30 letters represent the respective parts of my invention.

The figure illustrates a perspective view of my device.

The letter A represents the said halter-bridle, in which one length of hitch-rope a is 70 made to form the bit-rings b, cheek-cords c, and headstall d of the halter, as shown. This is done by suitably measuring off the length of the portion of the rope a required to form the 75 aforesaid head parts. Then, having bent or 80 twisted the rope into a round loop for the near-side bit-ring, as shown, fasten the same to the near end of the nose-strap e by stitching or riveting. Then, leaving a sufficient length 85 for cheek-cords c and headstall d, form the off-side bit-ring, as before, opposite the former

one; and, finally, after running a suitable ring on each branch of the fork-piece o, hereby made, join and fasten the end of the remainder of the rope to the main or hitch piece a, either 50 by wrapping or a thimble, h, of metal or leather, as shown. The usual forestall or frontlet, f, is riveted to the headstall, as shown, and is provided with a suitable ring riveted at or upon each end thereof. The throat-latch g is made of two suitable leather straps 55 riveted together in cruciform, as shown, and has its lower ends also riveted each to one of the said rings running on the branches of said fork-piece o, while the off-side upper end is 60 riveted to the ring on the forestall f, and the near-side upper end is snap-hooked to near end of said frontlet.

The above halter is readily converted into a bridle by fastening the rein bit-rings to the 65 loops b in any ready and suitable manner, with either buckle-straps or snap-hooks, and the cheek-cords and headstall can be covered with leather or canvas to prevent chafing.

As an article of manufacture, the above-described device is easily, quickly, and cheaply made, and is also durable, serviceable, and, while easily fitted to and worn by a horse or mule, readily convertible either into halter or bridle, or both. Therefore,

Having fully described my invention, what I claim as new, and desire to secure by Letters Patent, is—

An interchangeable or a combined halter and bridle, A, in which the bit-loops b, the 80 cheek-cords c, and the headstall d are all formed of one and the same piece of rope, in combination with the riveted leather frontlet f, nose-strap e, and cruciform throat-latch g, substantially as and for the purposes specified. 85

In testimony whereof I affix my signature in presence of two witnesses.

HENRY ROREBECK.

Witnesses:

GAWN LAMERY,

LEWIS H. ROREBECK.
